HEM PINNING IMPLEMENT
 Kurt M. Vogel, Fairfield, Conn.
 (506 Logan St., Bridgeport, Conn.)
 Filed Sept. 3, 1963, Ser. No. 306,239
 2 Claims. (Cl. 227—124)

The present invention relates to an adjustable hem pinning implement. It is customary in the fitting and finishing of certain garments, particularly ladies' skirts and dresses, for the tailor, dressmaker or housewife to turn and temporarily pin the hem of such garments while they are in place upon the wearer, the hem being thereafter permanently stitched and the pins thereupon removed. This is a laborious procedure and because of the difficulty of accurately placing the pins at a measured distance from the fold of the hem, the following stitching operation is both difficult and apt to result in an uneven hem line.

An object of the invention is to provide an implement by means of which a series of pins may be rapidly inserted in the hem, and to this end it is proposed to provide an implement in which a strip of adhered pin forming members are received, and which may be actuated to individually insert the members in inverted U-shape in the material to be pinned and form each said member into a substantially straight pin with the leg portions of the member in slightly offset parallel relation to the bridge portion.

A further object is to provide an implement of this character having adjustable gauge means to accurately position the fold of the hem at a pre-determined distance from the point at which the pin is applied, so that as the tailor, dressmaker or housewife successively applies the pins in spaced relation about the hem they will be uniformly spaced from the fold.

Other objects and advantages will become apparent from a consideration of the following detailed description taken in connection with the accompanying drawings wherein a satisfactory embodiment of the invention is shown. However, it will be understood that the invention is not limited to the details disclosed but includes all such variations and modifications as fall within the spirit of the invention and the scope of the appended claims.

In the drawings:

FIG. 1 is a side elevation of a hem pinning implement according to the invention, and showing the hem portion of a garment engaged therewith preparatory to pinning;

FIG. 2 is a similar view showing the implement in its operative position to apply a pin to the hem, the dot-and-dash lines showing an intermediate position of the actuating hand grip lever wherein the hem is clamped in position preparatory to pinning;

FIG. 3 is a front elevation of the implement as seen in FIG. 1;

FIG. 4 is a longitudinal vertical sectional view, partially broken away, taken along the line 4—4 of FIG. 3;

FIG. 5 is a transverse sectional view taken along the line 5—5 of FIG. 1;

FIG. 6 is a fragmentary perspective view showing the housing member and the anvil and adjustable gauge members of the implement in separated relation;

FIG. 7 is a front elevation, on an enlarged scale and partially in vertical section, with the hem portion of the garment in engaged relation therewith preparatory to pinning;

FIG. 8 is a horizontal sectional plan view taken along the line 8—8 of FIG. 7;

FIG. 9 is a front elevation showing the implement in its partially operated position to insert the leg portions of the pin forming member through the hem;

FIG. 10 is a similar view showing the implement in

2

fully operated position to form the pin forming member into a substantially straight pin;

FIG. 11 is a perspective view showing the hem portion of a garment with a pin in place;

FIG. 12 is a similar view showing the pin being extracted following the stitching of the hem;

FIG. 13 is a fragmentary side elevation of a modified form of the invention.

Referring to the drawings the hem pinning implement of the invention is adapted as shown in FIGS. 3 and 4 to contain a strip S of inverted U-shaped pin forming members 10 formed of thin bendable wire and adhered together, as by a suitable adhesive coating, so that they are readily separable from the strip, the device according to the invention being operable to force the side leg portions of a pin forming member through the material to be pinned and thereupon bend them into outwardly extending slightly offset substantially parallel relation to the bridge portion as seen in FIG. 11. A substantially straight pin is thus provided, which is retained by the slight offset bends against accidental slippage from the centralized position as seen in FIG. 11, while permitting easy manual removal by withdrawing in either direction as seen in FIG. 12, the leg portions being of sufficient length to permit them to be easily gripped by the fingers. The implement further incorporates adjustable gauge means to accurately determine the spacing of the pins from the fold of the hem.

In the exemplary embodiment of the invention illustrated in the drawings the implement comprises a housing member, preferably formed of sheet metal, consisting of a top wall 11, parallel side walls 12—12, and a hand grip portion 13 extending rearwardly from the top wall 11 and the upper portion of the side walls. In the lower portions of the side walls 12 there are respectively provided horizontal slots 14—14 disposed parallel to the top wall 11 and opening to the forward edges of the side walls to provide a throat space 15 for receiving the material to be pinned. The jaw portions 16 of the side walls below the slots 14 have their lower edges inclined downwardly and rearwardly and between these jaw portions there is mounted an anvil member 17 comprising a base wall 18 having a longitudinal slot 19 for cooperation with the adjustable gauge means as will hereinafter more fully appear, and side walls 20 secured as by welding to the inner sides of the jaw portions 16, the base wall being inclined downwardly and rearwardly in parallel relation to the lower inclined edges of the jaw portions and the upper edges of the side walls being parallel to and substantially flush with the lower edges of the slots 14. A forward extension 21 of the base wall is bent rearwardly in conforming relation to the convexly rounded forward ends 22 of the side walls 20 and is provided with outwardly extending anvil portions 23—23 seated in notches 24—24 in the upper edges of the side walls 20. Anvil grooves 25—25 are provided in the anvil portions for bending the leg portions of the pin forming members outwardly, as will hereinafter more fully appear, and the outer ends of the anvil portions are curved downwardly to provide for the smooth movement of the anvil in relation to material being pinned. The inner end surfaces of the grooves 25 are inclined or curved upwardly to the top surface of the anvil to provide camming surfaces to start the spreading of the leg portions as their ends are engaged with these camming surfaces. A rearward extension 26 of the base wall is bent upwardly therefrom between the rearward ends of the side walls and is provided with an aperture 27 for the purpose of anchoring an actuating spring of the implement as will hereinafter more fully appear.

A feed magazine for the strip S of pin forming members 10 is pivotally mounted within the housing member

in normally flush relation with the upper edges of the slots 14, and comprises an elongated channel member 28 having intermediate its ends a pair of pivot bearing apertured ears 29 struck from its base wall and extended downwardly in the plane of its side walls and engaged by a transverse pivot pin 30 supported by and extending between the side walls 12 of the housing member, this pivot pin being located rearwardly of and substantially in line with the slots 14 so that upon counterclockwise pivotal movement of the channel member 28 its forward end will swing downwardly within the space 15 into clamping relation with the material to be pinned. An elongated guide strip 31 of U-shape in cross section is secured as by welding to the base of the channel member 29, its side walls being inwardly spaced from the side walls of the channel member with their upper edges downwardly spaced from inwardly extending retaining flanges 32 provided at the upper edges of the side walls of the channel member to thus provide an inverted U-shaped guide space for the strip 30.

At the forward end of the channel member 28 there is provided a staple driving head consisting of a vertically disposed head member 33 of U-shape in cross section having its side walls secured as by welding to upward extensions 34 of the side walls of the channel member, the forward edge of the base wall of the channel member being inwardly offset from the forward walls of the head member 33 to provide an opening 35 through which the forward pin forming member 10 of the strip S is adapted to be driven during the pinning operation. The side walls of the channel member respectively have clearance grooves 36-36 extending upwardly from the ends of the opening 35, the base surfaces of these grooves being inclined upwardly and inwardly to allow clearance spaces for the side leg portions of the staple forming member 10 whereby they remain straight as they spread during the driving operation into parallel relation with the bridge portion, as will presently more fully appear. The driving means consists of a rectangular driver plate 37 guided at its side edges in grooves 38 formed by the right-angularly disposed adjacent surfaces of the head member, the upward extension portions 34, and a backing member 39 secured as by welding to the inner sides of the extension portions .

An actuating lever 40 provided with a lower rearwardly extending hand grip portion 41 is pivotally mounted on a transverse pin 42 supported by and extended between the side walls 12 of the housing and has its forward nose portion 43 engaged in an opening 44 in the driver plate 37 and projected through a vertical slot 45 in the forward wall of the head member 33. This lever is preferably formed of sheet metal, its two side portions being folded upwardly from the hand grip portion and disposed at the inner sides of the side walls 12 at each side of the channel member 28, and being brought together in the central plane of the implement above the channel member where they are secured together as by spot-welding to thus provide a lever in which the upper portion engaged with the pivot pin and the nose portion 43 are of double thickness. Arcuate slots 46 provided in the side portions of the lever in concentric relation to the pivot pin 42 are engaged by the pivot pin 30 to permit limited swinging movement of the lever about the pivot pin 42 as will presently more fully appear.

A coil spring 47 positioned against the under side of the channel member 28 adjacent the pivot pin 30 has one leg engaged in the aperture 27 of the rearward wall 26 of the anvil member and its lower leg engaged with the inner side of the hand grip portion 41 of the lever 40, and thus exerts pressure upon the lever in clockwise direction to normally position the hand grip portion 41 in the open relation with its forward end abutting the rearward wall 26 of the anvil member as seen in FIG. 1, to move the driver plate to its raised position within the head member of the magazine, and to swing the magazine in clockwise direction about the pivot pin 30 through engagement of

the nose portion 42 of the lever with the upper end of the slot 45 of the head member, the upper end of the head member being pressed against the top wall 11 of the housing member.

The strip S of pin forming member 10 is pressed forward in the magazine by means of a push shoe 48 of inverted U-shape in cross section slidably mounted upon the guide strip 31 and having a pair of apertured lugs 49-49 disposed within the channel of the guide strip. These lugs are slidably engaged by a rod 50 having a head 51 at its forward end, a spiral spring 52 being disposed about the rod between the rearwardly disposed lug and a locking member 53 secured upon the rearward end of the rod. This locking member has a finger grip extension 54 at its base and at one side it is provided with a lug 55 adapted to be turned into locking engagement with a shouldered notch 56 provided in one side wall of the channel member 28. By turning the lug out of locking engagement with the notch the push shoe may be removed for the purpose of inserting another strip S of pin forming members 10. A lug 57 formed upon the forward end of the upper side of the push shoe is adapted when the last pin forming member of the strip is in place beneath the driver plate to abut the inner side of the driver plate, to thus prevent the push shoe from entering the space beneath the driver plate when the last pin forming member of the strip has been driven.

The adjustable gauge for determining the spacing of the pins from the fold of the hem comprises an inclined transverse portion 58 disposed in parallel relation to the inclined base wall 18 of the anvil member and connected thereto for longitudinal sliding movement by means of a headed stud 59 riveted to the transverse portion 58 and slidably engaged in the longitudinal slot 19. A pair of outwardly bowed spring arms 60-60 extend upwardly from the outer ends of the transverse portion 58 at the outer sides of the side walls 12 of the housing member and span the longitudinal throat space 15 with their forward edges in a plane at right angles to the longitudinal axis of the throat space, so that as the gauge is longitudinally adjusted along the inclined wall 18 of the anvil member the forward edges of the arms are at all times at right angles to the plane of the material engaged in the throat space. At their upper ends the arms 60 are provided with pad portions 61-61 engaging the outer surfaces of the side walls 12 under spring pressure, each pad being provided with an embossed detent projection 62 which seats in one of a row of spaced indentations 63 provided in each side wall 12 and arranged along a forwardly and upwardly inclined line parallel to the inclined base wall 18 of the anvil member. The indentations 63 are evenly spaced, for example $\frac{1}{8}$ inch apart, and suitable calibration markings 64 are provided along the upper edges of the throat space 15 to indicate the distance of the gauge from the point at which the pin is inserted in the material.

In operation the material M having a folded hem H is inserted in the throat space 15 as seen in FIG. 1 with the fold abutting the gauge which has been set at the desired depth. Thereupon the lower hand grip 41 is squeezed toward the upper hand grip 13 first causing the head end of the magazine to swing downwardly into gripping relation with the material, as indicated by the dot-and-dash lines in FIG. 2, and then causing a pin forming member 10 to be driven through the material and spread into straight pin form, as indicated by the full lines in FIG. 2.

As shown in FIG. 9 the pin forming member is first driven through the gripped material with the side leg portions remaining perpendicular to the bridge portion until their ends contact the camming surfaces of the inner ends of the anvil grooves 25, whereupon they spread outwardly while still remaining substantially straight by virtue of the clearance grooves 36, finally assuming the position as seen in FIG. 10 with the side leg portion

slightly offset and parallel to the bridge portion. The slight bends between the side leg portions and the bridge portion prevent accidental slippage of the pin from its centralized position, and at the same time permit easy removal through slight pulling force exerted upon either leg portion, as seen in FIG. 12. In practice, the pins are removed from the hem after the same has been permanently secured by a line of stitching 64.

In FIG. 13 there is shown a modification of the invention in which the gauge member is slidably mounted upon the top wall 11 of the housing. In this case a longitudinal slot 19a is provided in the top wall which is slidably engaged by a headed stud 59a riveted to the transverse portion 58a of the gauge. Bowed springy side arms 60a—60a extend downwardly from the transverse portion at each side of the housing and span the throat space 15 at right angles to its longitudinal axis. Each arm is provided with an embossed detent projection 62a engaging one of a row of spaced indentations 63a in the side wall of the housing disposed along a line parallel to the top wall 11. The spacing of the indentations from the point at which the pin is driven is indicated by calibration markings 64a.

The implement of the invention may be conveniently held in one hand as a hem is being pinned with the throat space of the implement oriented to have the hem guided into it to the point where its fold engages the gauge whereupon initial squeezing pressure upon the hand grip portions causes the implement to grip and hold the hem and continued pressure swiftly applies the pin. Upon release of such pressure the implement is conveniently slid along the hem to the point where the next pin is quickly applied and so on until the entire hem is pinned.

What is claimed is:

1. In a hem pinning implement, housing means comprising parallel side walls, a horizontal longitudinally extending transverse top wall and an inclined longitudinally extending transverse bottom wall inclined downwardly and rearwardly relatively to said top wall, slot means in said side walls disposed parallel to said top wall and defining a horizontal longitudinally extending throat space opening to the forward end of said housing means for receiving material to be pinned, a magazine within said housing means at one side of said throat space for receiving a plurality of pin forming members and movably mounted for movement into said throat space to grip material disposed therein, each said member including a bridge portion and a pair of leg portions, anvil means at the other side of said throat space, driver means associated with said magazine arranged to drive individual

pin forming members therefrom in inverted U-shape toward said anvil means, manually operable means connected to said magazine and driver means adapted upon initial actuation to move said magazine into gripping relation with said material and upon continued actuation to impart driving movement to said driver means, said anvil means having anvil surfaces arranged to spread the leg portions of an individual pin forming member into outwardly extending substantially parallel relation to the bridge portion thereof as said leg portions are driven through said material and engaged with said anvil surfaces through driving pressure applied to the bridge portion, and gauge means for limiting the depth of insertion of material in said throat space comprising a transverse portion extending transversely across said inclined bottom wall, means connecting said transverse portion to said inclined bottom wall for longitudinal movement in parallel relation to said inclined bottom wall, and side arms extending from the ends of said transverse portion at the outer sides of said side walls in spanning relation to said horizontal throat space and including vertical transversely aligned forward edges disposed at right angles to the longitudinal axis of said horizontal throat space, and detent means for releasably fixing said gauge means in predetermined positions of longitudinal adjustment.

2. The invention as defined in claim 1, wherein said side arms are springy to engage said side walls under spring tension, wherein said inclined bottom wall has a longitudinally extending slot, wherein said means connecting said transverse portion to said inclined bottom wall comprises a headed stud secured to said transverse portion and slidably engaged in said longitudinal slot of said inclined bottom wall, and wherein said detent means comprises an inclined row of spaced detent formations on at least one of said side walls disposed parallel to said inclined bottom wall, and a detent formation on at least one of said said arms for selective engagement with one of said detent formations of said inclined row.
